UNITED STATES PATENT OFFICE

109,147

DESIGN FOR A MOTOR VEHICLE HEATER CASING OR SIMILAR ARTICLE

John L. Loughrey and Frank Acton, Columbus,
Ohio, assignors to Francisco Auto Heater Com-
pany, Columbus, Ohio, a corporation of Ohio

Application February 19, 1937, Serial No. 67,754

Term of patent 7 years

To all whom it may concern:

Be it known that we, John L. Loughrey and Frank Acton, citizens of the United States, residing at Columbus, in the county of Franklin and State of Ohio, have invented a new, original, and ornamental Design for a Motor Vehicle Heater Casing or Similar Article, of which the following is a specification, reference being had to the accompanying drawing, forming a part thereof.

Fig. 1 is a front elevation of a motor vehicle

heater casing or similar article showing my new design;

Fig. 2 is a side elevation thereof.

Fig. 3 is a top plan view thereof.

We claim:

The ornamental design for a motor vehicle heater casing or similar article as shown.

JOHN L. LOUGHREY.
FRANK ACTON.
